MUFFLER

Gail C. Starkweather, Kenmore, and Lucien L. Haas, Buffalo, N. Y., assignors to Buffalo Pressed Steel Company, Inc., Buffalo, N. Y.

Application June 14, 1937, Serial No. 148,068

9 Claims. (Cl. 181—48)

This invention relates to improvements in mufflers or silencers of the kind commonly used in connection with the silencing of the exhaust of internal combustion engines.

One of the objects of this invention is to provide a muffler having a conduit of improved construction through which the gases pass from the muffler. It is also an object of this invention to provide a muffler with an inner conduit formed of tapering sections arranged in telescopic relation to each other. Another object of the invention is to provide a muffler of the type which is provided with acoustic chambers arranged about an inner conduit formed of a plurality of tapering and 15 interfitting sections so arranged with relation to the acoustic chambers as to improve the silencing action of the muffler. Another object is to provide a muffler of this kind in which the telescoping portions of adjacent sections are supported in correct relation to each other by means of baffles which also form the walls of resonator chambers surrounding said conduit. It is also an object of this invention to provide a muffler in which tapering perforated sections telescoping one within another form a conduit of a muffler which results in a greater flow of gases and sound waves outwardly through the perforations of the sections and through the different chambers of the muffler.

Other objects of this invention will be apparent 20 from the following description and claims.

In the accompanying drawing:

Fig. 1 is a longitudinal central sectional elevation of a muffler embodying this invention.

Fig. 2 is a fragmentary central longitudinal 35 sectional elevation of a muffler of modified construction.

Fig. 3 is a transverse section thereof, on line 3—3, Fig. 2.

The muffler may have an outer housing of any 40 suitable or desired form, that shown including an outer shell A having a head B at one end thereof which may be formed so as to provide an inlet duct b to which an exhaust pipe from an engine may be connected, and the other end of the 45 shell may be provided with a similar head C provided with a duct c for the discharge of gases from the muffler and to which a tail pipe may be connected. The heads shown in Fig. 1 are provided with shoulders at 10 and 11 arranged for 50 engagement with the ends of an intermediate shell 12. This shell forms with the outer shell A a space which may be divided into separate chambers, for example, by means of an annular transverse baffle 14 arranged between the outer and 55 intermediate shells. A housing and intermediate

shell of other construction may, of course, be provided if desired.

The conduit shown in Fig. 1 and embodying one form of this invention includes a plurality of tapering sections or units 16, 17, 18 and 19, 5 the sections 16, 17 and 18 being all substantially identical in construction and the section 19 being longer than the other sections. Each of the sections 16, 17 and 18 is tubular in form and of tapering or frusto-conical shape with the larger 10 end approximately of the same diameter as the exhaust pipe or inlet duct b of the muffler and with the smaller end approximating the diameter of the discharge duct c of the muffler, although these dimensions may vary considerably depending upon the particular engine upon which the muffler is to be used. The taper of the sections of the conduit preferably is sufficient to enable the smaller end of a section to extend to a substantial extent into the larger end of an adjacent 15 section. The longer section 19 may be of less taper than the other sections and, if desired, may be of uniform diameter throughout its length. While we have shown in Fig. 1 four sections, it will be obvious that any desired number of these 20 sections may be employed, and the end sections may be connected with the heads B and C of the muffler in any suitable or desired manner. In the construction shown in Fig. 1, the muffler section 16 is supported from the intermediate shell 12 by 30 means of a transverse baffle or shouldered ring 20, having a shoulder or flange 21 of a diameter such as to fit snugly within the intermediate shell 12 and an inner shoulder of smaller diameter 22 which is adapted to fit telescopically with reference to the section 16, and the baffle 20 may be secured to the intermediate shell 12 and section 16 by welding or other suitable means.

At the other end of the muffler, the last section 19 is secured to the intermediate shell by means 40 of a similar baffle or shouldered ring member 24, and if desired, an additional baffle 25 may be arranged between the intermediate shell 12 and the conduit member 19 to divide the space between the intermediate shell and the conduit member 45 into two separate chambers.

The conduit sections 16 to 19 inclusive, are preferably perforated throughout the greater portion of their lengths. Any suitable type of perforation or opening may be employed, rectangular 50 slits 28 being shown in the construction illustrated, and if desired, the sections 16, 17 and 18 of the conduit may be provided in the ends thereof arranged within adjacent conduit sections with holes or apertures 29.

Each of the sections 16 to 18 inclusive has a substantial portion of its smaller end extending into the larger end of an adjacent section, so that the apertures 29 near the smaller end of the section will be arranged within the larger end of an adjacent section while the other apertures 28 will establish communication between the interior of the section and the space between the section and the intermediate shell 12. If desired, also the edge portions of the smaller ends of the sections 16 to 18 inclusive may be turned inwardly to any desired extent as indicated at 30, so that the gases passing through the sections are slightly retarded both by the tapered form of the sections and by the inwardly turned or flanged ends 30. The inturned ends of the sections supplement the tapers thereof and, consequently, the taper of a section may be decreased, if the turned over end 30 thereof extends inwardly to a greater extent.

In order to support the several sections in correct relation to each other and at the same time to divide the space between the inner conduit and the intermediate shell 12 into a plurality of chambers, I provide annular baffles 32 each of which has substantially cylindrical flanges engaging the inner face of the intermediate shell 12 and radially extending flanges which form walls of the chambers between the conduit and the intermediate shell. The inner ends of these transversely extending walls are constructed to engage portions of adjacent sections of the conduit, preferably at or near their telescoping portions. For this purpose, the baffles may, for example, be provided with substantially axially extending flanges 33 which extend into the larger ends of the sections 17, 18 and 19, and which are preferably so formed as to also engage those portions of adjacent sections which telescope into the larger ends of the sections 17, 18 and 19. This may be accomplished by offsetting the end portions of the flanges 33 as shown at 34 so as to extend into contact with the smaller portions of the adjacent sections. By means of this construction, the baffles 32 serve the two-fold purpose of forming the end walls of chambers 35, 36, 37, and 38 and also securing the sections of the conduit in correct relation to each other and to the intermediate shell 12. Other means for supporting the sections of the conduit may be provided, if desired.

In the operation of the muffler described, gases and sound waves entering through the duct b pass into the first section 16 of the inner conduit and because of the tapering or frusto-conical shape of this conduit, and because of the inwardly extending edge 30 of the section, if such edge is used, the flow of gas pulsations through the section will be somewhat retarded and equalized and the peaks of the pressure pulsations will pass through the apertures 28 of the conduit section 16 into the chamber 35 while the greater portion of the gases pass through the conduit section 17. In this section, the gases are subjected to a similar action as in the conduit 16, although to a lesser extent since the pressure pulsations entering this section of the conduit will be of materially less intensity than those which originally entered the section 16. A similar action occurs in the conduit sections 18 and 19.

Because of the taper of the conduit 16 and the inwardly flanged end 30, the peaks of the pressure waves passing into the chamber 35 will pass from the chamber 35 through apertures or openings 40 in the intermediate shell into an outer

chamber 41 arranged between the intermediate and outer shells and will pass from this chamber through another set of apertures or openings 42 in the intermediate shell into the chamber 36 from which they will again enter the section 17 through the apertures therein. In the conduit section 18 a similar action occurs in that the peaks of the pressure pulsations entering this section and passing outwardly through the apertures 28 therein will pass into an intermediate chamber 37 and through apertures or openings 43 in the intermediate shell into an outer chamber 44 from which they may return to the conduit section 19, either through apertures or openings 45 or 46 of the intermediate shell and through the apertures 28 in the conduit section 19.

The apertures 29 adjacent to the smaller ends of the conduit sections 16, 17 and 18 decrease the resistance to flow of gases through the conduit in that they break up any tendency of the jets of gases discharged through the smaller ends of the conduit sections from forming partial vacuums in the spaces between telescoping parts of adjacent sections.

In Figs. 2 and 3, we have illustrated how the improvements herein described may be incorporated in a muffler of somewhat different construction. In this muffler, an outer shell D is provided with inlet and exhaust heads E and F respectively having inlet and discharge ducts e and f. In this case, an intermediate shell 50 is employed which is shorter than the distance between the heads E and F and the ends of which are supported from the inner conduit. This may be accomplished in any suitable or desired manner, and in the construction illustrated we have provided a short tubular part 51 which fits within the duct e and also within the larger end of the first conduit section 52, which may be substantially similar in construction to the section 16 shown in Fig. 1. At the other end of the muffler the last conduit section 53 extends into and is welded or otherwise secured to the inner face of the duct f of the discharge head F. The ends of the intermediate shell 50 may be depressed or deformed at intervals around the circumference as indicated at 54 into contact with the adjacent sections of the inner conduit, while other portions of the ends of the intermediate conduit may remain in spaced relation to the inner conduit and form therewith openings or channels 55 which connect those inner chambers adjacent to the ends of the intermediate shell with the outer chambers arranged between the intermediate shell and the outer shell B. These channels 55, consequently, form openings which may be employed in place of the apertures or openings 40 and 46 formed in the inner shell 12 shown in Fig. 1. The channels also serve as bottle necks in conjunction with outer resonator chambers formed between the intermediate and outer shells. Otherwise the muffler may be similar in construction and operation to the muffler shown in Fig. 1.

We claim as our invention:

1. A muffler having a housing provided with an inlet and an outlet, an intermediate shell in said housing and forming therewith a resonator chamber in communication with the interior of said shell, and a conduit arranged to receive gases from said inlet and discharge the same to said outlet, and arranged in and spaced from said intermediate shell and including a plurality of similar perforated sections which are substantially uniformly tapered from their gas receiving ends

to their gas discharge ends and each having its end of smaller diameter extending into and spaced from an adjacent end of another section, whereby the taper of the tapered sections causes 5 gases to flow through the perforations thereof into the space between said conduit and intermediate shell and through the apertures in said intermediate shell into said resonator chamber.

2. In a muffler, the combination of an outer 10 shell, an intermediate shell in said outer shell and spaced therefrom to form therewith a chamber and having an opening which establishes communication with the interior of said intermediate shell and said chamber, an inner conduit

15 arranged within and spaced from said intermediate shell and including a plurality of substantially similar tapered and perforated sections arranged with the small end of a section extending into and spaced from the large end of an adjacent section, said tapered sections forming a plurality of restrictions in said conduit which cause 20 gases to flow through the perforations of said sections and into the space between said conduit and intermediate shell and into said chamber.

25 3. A muffler having a conduit comprising a plurality of substantially similar nested sections which taper substantially uniformly from end to end thereof, each section being perforate and having its smaller end telescoped within the 30 larger end of an adjacent section.

35 4. A muffler having a conduit comprising a plurality of substantially similar nested sections which taper substantially uniformly from end to end thereof, each section being perforate and having its smaller end telescoped within the larger end of an adjacent section, and having the edge of its smaller end turned inwardly to restrict the flow of gas through the same.

40 5. A muffler having outer and intermediate shells, a conduit arranged in said intermediate shell and comprising a plurality of substantially similar nested perforate sections, each section having its smaller end telescoped within the larger end of an adjacent section, and a plurality of substantially similar transverse annular baffles 45 secured within said intermediate shell and supporting said sections in correct relation to each other and forming sound attenuating chambers between said conduit and said intermediate shell, said baffles also having parts extending between telescoped

portions of said sections to space said portions from each other.

6. A muffler having outer and intermediate shells, a conduit arranged in said intermediate shell and comprising a plurality of substantially similar nested perforate sections which taper substantially uniformly from end to end thereof, each section having its smaller end telescoped within the larger end of an adjacent section, and a plurality of substantially similar transverse 10 annular baffles secured within said intermediate shell and having an axially extending portion on its inner edge which extends between telescoping portions of adjacent sections.

7. A muffler having a conduit comprising a plurality of substantially similar nested sections each having a substantially uniform taper from end to end thereof, each section being perforate and having its smaller end extending into the larger end of an adjacent section, annular spacing means arranged between the larger end of a section and the portion of said first section extending into said larger end and having a portion extending outwardly beyond said larger end, and a shell arranged about said conduit and to 25 which said outwardly extending portion is secured.

8. A muffler having a conduit comprising a plurality of nested tapering sections, at least one of said sections being perforate and having its 30 smaller end telescoped within the larger end of an adjacent section and having perforations in the portion thereof arranged within said adjacent section to reduce the tendency of the ejector action of said section to form a partial vacuum 35 about said portion.

9. A muffler having a conduit comprising a plurality of substantially similar nested sections tapering substantially uniformly from end to end thereof, each section being perforate and having its 40 smaller end telescoped within the larger end of an adjacent section, an intermediate and an outer shell arranged one within the other, and a baffle arranged within said intermediate shell and supporting the telescoping portions of adjacent sections, said intermediate shell having openings arranged forwardly and rearwardly of said baffle.
